(57) CLAIM

The ornamental design for a lite for doors and entryways, as shown and described.

DESCRIPTION

FIG. 1 is a front elevational view of my design;

FIG. 2 is a front perspective view thereof;

FIG. 3 is a front elevational view of an alternative embodiment of FIG. 1; and,

FIG. 4 is a front perspective view of the alternative embodiment of FIG. 3.

The rear elevational view of each of FIGS. 1 and 3 is a mirror image thereof.
